UNITED STATES PATENT OFFICE.

MICHAEL P. McNULTY, OF WHITNEY, NORTH CAROLINA.

RAILWAY CONSTRUCTION.

1,222,432.

Specification of Letters Patent. Patented Apr. 10, 1917.

Application filed July 10, 1916. Serial No. 108,419.

To all whom it may concern:

Be it known that I, MICHAEL P. McNULTY, a citizen of the United States, residing at Whitney, in the county of Stanly and State of North Carolina, have invented new and useful Improvements in Railway Construction, of which the following is a specification.

The present invention relates to improvements in railway construction.

An object of the invention is to produce a tie comprising a trough-shaped metal member having spaced sides and a central compartment, reinforced plastic material filling the spaces between the sides and filling the central compartment, and removable means being arranged in the channeled ends of the ties and secured thereto for supporting and for retaining the rails upon the ties.

With the above and other objects in view the improvement resides in the construction, combination and arrangement of parts set forth in the following specification and falling within the scope of the appended claims.

In the drawings:

Figure 1 is a plan view illustrating rails supported upon and secured to ties constructed in accordance with the present invention,

Fig. 2 is a central longitudinal sectional view, upon an enlarged scale, taken through one of the ties and the rails secured to the ties,

Fig. 3 is a transverse sectional view approximately on the line 3—3 of Fig. 2,

Fig. 4 is a perspective view of one of the ties with the rail supporting and engaging members thereon,

Fig. 5 is a similar view with the rail supporting members removed,

Fig. 6 is a bottom plan view of the tie,

Fig. 7 is a perspective view of the metallic or shell portion of the tie,

Fig. 8 is a perspective view of one of the metal rail engaging members,

Fig. 9 is a similar view of one of the blocks,

Fig. 10 is a side elevation of another form of the metallic rail engaging member,

Fig. 11 is a perspective view of the end of a rail which may be employed,

Fig. 12 is a similar view of the end of another rail which may be employed, and

Fig. 13 is a transverse sectional view through the center of the construction illustrated in Fig. 7.

In the drawings, 15 designates the rails and 16 the ties which support the rails.

The rails 15 are of the ordinary construction having the usual bolt openings passing through the webs thereof, but if desired the rail, as illustrated in Fig. 11, may have its ends integrally formed with a plurality of laterally extending studs 17 or as illustrated in Fig. 12, the rail end may be provided on each side with a single substantially rectangular lug or stud 18 projecting from the opposite sides of its web.

Each of the ties 18 includes an inner metallic channel member which from its ends, to a suitable distance from its center, is rectangular in cross section, and the parallel sides of the said ends have their edges bent or otherwise provided with longitudinally extending grooves 20. The central portion 75 of the channeled members comprises a substantially V-shaped trough and is divided from the rectangular end portions by vertically disposed partitions 21—21 which project above the edges of the said channeled member, as shown in the drawings. The tie also includes an outer substantially U-shaped metallic member 22 that is adapted to inclose the inner metallic member 19 thereof, so that the sides 23 of the said member 22 are spaced from the sides 24 of the inner member 19 and the member 22 has its central portion formed with an inturned substantially V-shaped trough 22' which is adapted to receive the referred to trough of the inner member 19. The base 26 of the member 19 rests on the horizontally straight base 25 of the outer member 22, and if desired both the inner and outer members may be constructed of sections which are suitably connected, at the base portions thereof, and the base 26 of the member 19 is connected with the base 25 of the member 22, preferably by rivets, as disclosed in the drawings. It

is to be understood that when the member 22 is constructed from a single element it has its base also connected with the base of the inner member 19. If desired the partitions 21 may extend over the top edges of the sides of the inner member 19 and be arranged in a line with the outer edges of the sides 23 of the outer member 22, longitudinally extending members 27 connecting the partitions and these members, if desired, may be formed integral with the sides 24 of the inner member 19 or with the sides 23 of the outer member 22. The sides 23 of

the outer member 22 are provided with longitudinally extending openings 28, and the bottom 25, at the space between the sides 23 of the outer member and the sides 24 of the 5 inner member are likewise provided with elongated openings 29. Both of the openings 28 and 29 extend almost the length of the tie and the said openings are provided to permit of the plastic filler 30 which is 10 inserted in the space between the sides of the inner and outer member, to pass through the said openings and thus obtain a firmer hold upon the metallic shell of the tie. The box formed at the central portion of the tie 15 and provided by the partitions 21-21 and the longitudinal members 27 connecting the said partitions is also adapted to have tamped therein a filler of plastic material, indicated by the numeral 31, and this filler 20 may have, and preferably has, arranged therein metal reinforcing rods. The side filler 30 is reinforced by the vertically disposed arms 32 of substantially U-shaped metal rods 33, the connecting member for 25 the rods being disposed transversely of the bottom or base 25 of the tie.

Passing longitudinally through the box at the center of the tie and if desired secured to the partitions 21 as well as being provided 30 with means for engaging with the plastic filler 31 in the said box, is a rod or bolt member 34. This bolt member is disposed centrally of the tie, and is preferably arranged above the grooves 20 in the inner member 19 of the tie and has its ends terminating with or slightly inward of the ends 35 of the tie. The ends of the bolt 34 are threaded, as at 35.

The open ends of the tie are adapted to 40 receive each a substantially rectangular block 36, and the rail engaging members 37 rest upon these blocks and are secured thereto in a manner which will presently be described. The blocks may be in the nature of 45 wooden blocks and each of the same, at a suitable distance from its center, and upon its upper face is formed with depressions 38, while each of the blocks is provided with a longitudinally extending opening 39 that 50 communicates with the depressions, and the bolt members 34 are adapted to pass through the openings 39.

The rail engaging members are arranged in pairs, two of the co-acting members being positioned upon each of the blocks 36, and each of the said rail engaging members includes a horizontally straight flange 40 upon which the base flanges of the rails are received and vertically disposed plates 55 41 which have their inner faces shaped to correspond with and which are adapted to be received in the fishing spaces on the sides of the rails. The plate of one of the rail engaging members may be provided with studs 60 42 which are adapted to be received in the

bolt openings of the webs of the rails, or as shown in the drawings, the said plates may be provided with openings to receive the studs 17 in the rail ends, while still again the plates may be provided with elongated 70 openings 44 to receive each one of the lugs 18 upon the rails. The members 40 and 41 are of a width preferably greater than the cross sectional width of the tie and integrally formed with the flanges 40 and connected to the vertical plates 41 by integral members 45 are outwardly extending hoods 46. The hoods 46 include spaced sides which have their lower edges formed with tongues or flanges 47, which are adapted 80 to ride in the grooves 20 of the central channeled member 19 of the tie. The outer straight angular ends of the hoods, indicated by the numerals 48, depend a suitable distance below the tongues or flanges 47, 85 and these end plates are adapted to contact with the ends of the blocks 36. The end plates are also provided with openings 49 through which the rod 34 passes, and the portion of said end plates below the said 90 opening 49 may be provided with additional openings for the reception of securing elements 50 which enter the blocks 36. The upper plate of each of the hoods forward of its outer plate 48 is formed with a downwardly extending ear 51, which is adapted to be received in one of the depressions 38 in the blocks 36, and is provided with an opening which receives the rod 34.

The threaded ends of the rod 35 are engaged by nuts 51' which may also contact with washers 52 disposed upon the rod 35 between the end plates of the hoods and the said nuts, and by this arrangement it will be noted that the rail securing elements 95 may be effectively sustained at a desired position with relation to the tie, and also that the blocks, together with the said rail securing elements, may be easily and quickly removed from the tie. If it is desired that only the outer rail engaging element be removed this can be readily accomplished without interfering with the inner rail engaging element or member as will, it is thought, be readily understood. The longitudinally extending rod may be threaded throughout and, if desired, adjusting elements, in the nature of nuts 52' may be positioned upon the rod between the blocks 100 and the partitions so that when the said bolts are screwed in the direction of the blocks and the outer nuts 51' are loosened upon the rod the blocks and the rail engaging members carried thereby may be sustained out of contact with the partitions, and thus it will be noted that the blocks and the rail engaging elements may, if desired, be sustained at any desired position upon the tie.

It is to be noted that the substantially cen- 130

tral V-shaped portion of the tie will permit of the tamping of the roadbed therein, so as to effectively retain the tie against longitudinal movement, while the flat base of the tie to the opposite sides of the said central V-shaped portion will prevent the sinking or lateral movement of the said tie, and the additional advantages of the structure will, it is thought, be apparent to those skilled 10 in the art to which such invention appertains.

Having thus described the invention, what I claim is:

1. A tie comprising a substantially U-shaped metallic member having its sides each comprising a pair of spaced members, a plastic filler between the spaced members comprising the sides, blocks in the tie, means for adjusting the blocks longitudinally of the tie, and rail engaging means associated with the said blocks.

2. A tie comprising a substantially U-shaped metallic member having its sides each comprising a pair of spaced members, a plastic filler between the spaced members comprising the sides, U-shaped reinforcing rods having their arms embedded in the filler and their connecting portions arranged upon the bottom of the tie, blocks in the tie 30 at the ends thereof, means for adjusting the blocks longitudinally of the tie, means for holding the blocks in such adjusted position, and rail engaging means associated with the said blocks.

3. A tie comprising a substantially U-shaped metallic member having its sides each comprising a pair of spaced members, a plastic filler between the spaced members comprising the sides, blocks in the tie, 40 means for adjusting the blocks longitudinally of the tie, rail engaging means associated with the blocks, and guide means upon said rail engaging means co-acting with the inner side walls of the tie.

4. A tie comprising a substantially U-shaped metallic member having its sides each comprising a pair of spaced members and having spaced central partitions, a plastic filler between the partitions and the spaced members comprising the sides, blocks in the tie, means for securing the blocks in contact with the partitions, and rail engaging means secured upon said blocks.

5. A tie comprising a substantially U-shaped metallic member having its sides comprising each two spaced members, transverse partitions in the tie, connecting members for the partitions, a plastic filler between the said partitions and the connecting members therefor, a plastic filler between the members comprising the sides, blocks in the tie and into contact with the partitions, and rail engaging means associated with 65 said blocks.

6. A tie comprising a metal member which is substantially U-shaped in cross section and which has its sides comprising each two spaced members, transverse partitions in the tie to the opposite sides of the center 70 thereof, a plastic filler between the members comprising the sides, a longitudinally extending threaded rod centrally connected to the partitions and to the plastic filler between the partitions, blocks in the tie having openings through which the rod passes, rail engaging members resting upon the blocks and connected by the rod, and nuts for the threaded ends of the rod.

7. A metal tie which is substantially U-shaped in cross section and which has its sides formed each of two spaced plates, transverse partitions in the tie to the opposite sides of the center thereof, connecting members for the partitions, a plastic filler 80 between the partitions and the connecting members, a plastic filler between the spaced members comprising the sides of the tie, a longitudinally extending rod centrally connected to the partitions and to the plastic 85 filler between the partitions, blocks in the ends of the tie and having openings through which the rod passes, rail engaging members upon the blocks, said rail engaging members including hoods which straddle the 90 sides and the ends of the blocks, and the rod also passing through the said end members of the hoods, and nuts threaded upon the rod.

8. A tie including a metal shell which is 100 substantially U-shaped in cross section and which has its sides each constructed of a pair of spaced parallel plates, the inner side plates having longitudinally extending grooves, transverse partitions in the tie to 105 the opposite sides of the center thereof, connecting side plates for the partitions, a plastic filler between the partitions and the connecting plates therefor, a plastic filler between the spaced plates comprising the sides 110 of the tie, a longitudinally extending rod centrally secured to the partitions and to the plastic filler between the partitions, blocks in the channeled ends of the tie having openings through which the rod passes, rail engaging members upon the blocks, each of 115 said rail engaging members including a hood which comprises side members that engage with the sides of the block and an end member which engages with the ends of the 120 block, ears depending from the top plates of the hoods and having openings to receive the rods, and said rod passing through the end plates of the hood, ribs upon the side members of the hoods received in the referred to grooves, and nuts screwed upon the rod, as and for the purpose set forth.

9. A tie comprising a member having its sides each comprising a pair of spaced walls, and which is substantially rectangular at 130

- the ends thereof and which is substantially V-shaped at the center thereof, a plastic filler between the spaced members comprising the sides, blocks in the end members of
- 5 the ties, means for longitudinally adjusting the blocks in the tie, and rail engaging means associated with said blocks.
10. A tie comprising a metal body and having its side walls each formed of two spaced members, said members, at the ends of the tie being vertically straight and being inclined inwardly to the center of the bottom of the tie at the central portion of the said tie, the outer members of the sides
- 15 having openings therein, a plastic filler between the members comprising the sides and filling the referred to openings, partitions dividing the central V-shaped portion of the

tie from the rectangular ends thereof, longitudinally adjustable members in the said ends, and rail supporting elements associated with said adjustable members.

11. A tie comprising a member having trough-shaped ends and a solid central portion which is V-shaped in cross section, the inner side walls of the ends of the tie having longitudinally extending grooves, rail supporting elements received in the ends of the tie and engaging with the grooves, and elements connected with the center of the tie and co-acting with the said rail engaging elements for sustaining the same adjusted in the ends of the tie.

In testimony whereof I affix my signature

MICHAEL P. McNULTY.
